G. MEYER,
LIGHTNING ROD CONNECTOR,
APPLICATION FILED APR. 1, 1920.

1,373,519.

Patented Apr. 5, 1921.

UNITED STATES PATENT OFFICE.

GEORGE MEYER, OF VANDYNE, WISCONSIN.

LIGHTNING-ROD CONNECTOR.

1,373,519.

Specification of Letters Patent.

Patented Apr. 5, 1921.

Application filed April 1, 1920. Serial No. 370,587.

To all whom it may concern:

Be it known that I, GEORGE MEYER, a citizen of the United States, residing at Vandyne, in the county of Fond du Lac and State of Wisconsin, have invented certain new and useful Improvements in Lightning-Rod Connectors; and I do declare the following to be a full, clear, and exact description of the invention, such as will enable others skilled in the art to which it appertains to make and use the same.

This invention relates to improvements in lightning rod connectors.

An object of the invention is to provide a connector of the above mentioned type which is so designed that it will effectively connect the collector cables, which extend from the lightning rod, to the horizontal ground or conductor cable which extends across the roof of the structure on which the device is to be installed.

Another object of the invention is to generally improve upon the construction of similar connectors by providing one which is more effective in use, easier to install, of greater strength, more durable, and costs but little more to manufacture than other connectors.

Other objects and advantages of the invention will be apparent during the course of the following description.

In the accompanying drawings forming a part of the specification and in which like numerals are employed to designate like parts throughout the same:

Figure 1 is a side elevation of a connector constructed in accordance with my invention, showing the same in use.

Fig. 2 is an elevational view of a connector as it appears preparatory to being placed in use.

Fig. 3 is a view like Fig. 1, showing a different type of conductor or cable associated with my connector.

Figs. 4 and 5 are transverse sectional views taken on the lines 4—4 and 5—5 respectively of Fig. 1.

In the drawing, wherein for the purpose of illustration is shown a preferred embodiment of my invention, the numeral 1 designates a portion of a lightning rod, which is of tubular formation. It is to be understood, that this rod will be provided with the usual collector point, and the rod will be supported from the structure by a suit-

able brace, these parts not being shown. Fitted into the pipe 1 and contacting with the aforesaid collector point are cables 2 which may well be termed "collector cables." These collector cables extend beyond the lower end of the pipe 1 in diverging relationship, and are connected by means of my connector, with the ground cable 3. As is well known, this ground cable, which is also sometimes known as a conductor cable, extends horizontally across the roof of a building, and down the sides thereof, its free ends being embedded in the ground so that the charge will be delivered to a point of safety.

My connector is in the form of a body member 4, and it includes a base section 5, from which side sections 6 extend. These side sections diverge from the base section and are connected together, and at this point are provided with a threaded attaching eye 7, by means of which the device is detachably connected to the lower end of the pipe 1.

From the foregoing, it will be seen that the body member is in the form of a triangular open frame. Examination of the drawings will disclose the fact that each of the sections 5 and 6 are of channel formation in cross-section. With this construction the collector cables 2 may be seated in the side section 6, and effectively connected at their free ends with the ground cable 3 which is seated in the base section 5. To hold the cables in place in the channels, I provide the latter with malleable prongs 8 which may be bent over the cables in the manner shown.

While I have shown two collector cables in use, I desire it to be understood that a single cable may be used. However, it is my desire to separate the portion of the cable which extends beyond the pipe 1 in the manner shown, so that the current or charge which passes through the cable will be more equally distributed and thus prevent overcharging of any of the cables, which oftentimes occurs with lightning rod structures now in use. It is for the above reason that I form my connector of triangular shape. It is to be mentioned here that my connector is made of brass or other suitable material, and it is extremely strong and durable, and will withstand rough usage and heavy shocks.

From the foregoing description it will be

seen that I have perfected an extremely useful lightning rod connector, which will assure that the connection between the collector cable and ground cable is proper. It 5 is extremely strong and is very easy to install, and may be used with various types of cables which are used in practice. It may be stated here that in Fig. 3 I have disclosed a different type of ground cable. 10 Examination of this figure will disclose the fact that my connector may be as effectively used with this type of cable, as well as with the type shown in Fig. 1. By making the connector of brass or other like material, 15 it will bear violent shocks without fracture, to which the ordinary type of connectors are liable.

A careful consideration of the foregoing 20 description taken in connection with the accompanying drawings will enable persons skilled in the art to which this invention appertains to acquire a thorough understanding of the same, therefore, further description is deemed unnecessary.

25 It is to be understood that the form of my invention herein shown and described is to be taken as a preferred form of the same, and that various minor changes in the shape, size and arrangement of parts may be resorted to without departing from the spirit 30 of the invention or the scope of the subjoined claims.

I claim:

1. A lightning rod connector comprising a body member, including a base section, 35 from which diverging connected side sections extend, thus forming an open triangular frame, each of said sections being of channel formation in cross-section and provided with malleable tongues to be bent 40 over the wires which are placed in them, and a screw-threaded attaching eye at the connecting point of the side sections.

2. In a lightning rod connector, the combination with a ground cable, and tubular lightning rod support having a pair of collector cables extending from its open end; of a body member, including a base section, 45 from which diverging side sections extend, each of said side sections being channel-shaped in cross-section, the ground cable being seated in the base section and the collector cables in said side sections, the last named cable being in contact with the ground cable, all of said sections being provided with malleable tongues which are bent 50 over the cables, and an integral attaching eye at the connecting point of the side sections to which the tubular rod support is 55 detachably connected.

60 In testimony whereof I have hereunto set my hand.

GEORGE MEYER
